UNITED STATES PATENT OFFICE

131,934

DESIGN FOR A SHOE

Neal Elmore, New York, N. Y.

Application September 16, 1941, Serial No. 103,378

Term of patent 7 years

To all whom it may concern:

Be it known that I, Neal Elmore, a citizen of the United States of America, residing at New York, county of New York and State of New York, have invented a new, original, and ornamental Design for a Shoe, of which the following is a specification, reference being had to the accompanying drawing, forming part thereof, wherein:

I claim:

The ornamental design for a shoe, as shown.

NEAL ELMORE.
